Primary Examiner — Jennifer L Watkins

(57) CLAIM

The ornamental design for a bag, as shown and described.

DESCRIPTION

- 1.1 is a perspective view of a bag in a first position.
- 1.2 is a perspective view of the bag in a second position.
- 1.3 is a perspective view of the bag in an open position.
- 1.4 is a front view of the bag of 1.1.
- 1.5 is a right side view of the bag of 1.1.
- 1.6 is a back view of the bag of 1.1.
- 1.7 is a left side view of the bag of 1.1.
- 1.8 is a bottom view of the bag of 1.1.

The dashed lines in 1.6 depict claimed stitching. The circular portions of the article shown in broken lines in 1.8 form no part of the claim.
